2 Sheets-Sheet 2

Patented Nov. 5, 1929

My invention relates to improvements for refrigerating coils for storage places, and it consists in the combinations, constructions, and arrangements, hereinafter described and claimed.

An object of my invention is to provide a refrigerating coil which may be disposed along the walls of the storage compartment, thus taking up a minimum amount of space.

This construction permits radiating fins of the required area to be connected to the cooling pipes without taking up any more actual storage room in the storage compartment and without the necessity of providing a larger expansion header. An expansion header and cooling pipes of standard size may be manufactured; then fins may be added to give correct coil size at the time of installation for various sized compartments.

A further object of my invention is to provide a device of the type described which has more cooling effect than a standard cooling refrigerating coil which takes up one-fourth to one-third the total storage area of the box. Furthermore, the cooling fins are so arranged as to cause more complete circulation of air thru the box or compartment, the movement of air being so rapid because of lack of obstructions as to permit the coil to operate at a higher temperature than other coils now on the market, yet keep the temperature within the compartment at the required point. This higher temperature of the cooling coil prevents the pipes from becoming coated with frost and thus permits the device to operate far more efficiently.

Other objects and advantages will appear in the following specification, and the novel features of the invention will be particularly pointed out in the appended claims.

My invention is illustrated in the accompanying drawings, forming a part of this application, in which—

Figure 1 is a front view of the device,

Figure 2 is a side view of the device, showing the side of the box and the radiating fins connected to the cooling pipes.

Figure 3 is an enlarged detail view of a portion of the device, showing the U-shaped pipes and the fins.

Figure 4 is a section along the line 4—4 of Figure 3.

Figure 2 is a section along the line 2—2 of Figure 1.

Figure 3 is an enlarged detail view of a portion of the device, and

Figure 4 is a section along the line 4—4 of Figure 3.

In carrying out my invention, I provide a box 1 of any desired size and having storage shelves 2 therein. I dispose the expansion header in the upper left hand corner and connect this tank 3 by pipes 4 to a compressor 5 and a cooling coil 6 in the usual manner.

One set of refrigerating coils 7 extends from the bottom of the tank 3 across the top of the box, while the other set 8 projects downwardly along the side of the box as shown in Figures 1 and 2. The unit as manufactured consists of the tank 3 and stub pipes 7' and 8'. To these pipes are secured the U-shaped pipes 7 and 8, the connection being effected by a novel joint, now to be described.

A radiating fin 9 is secured to the stub pipes 7' by solder or other suitable fastening means and a fin 10 is secured to the stub pipes 8'. A fin 11 of the required area for the box is provided with a U-shaped bend 12 and with openings 13 and 14 for receiving the pipes 7' and 8' respectively.

In Figure 3, I show the fin 10 as being bent and provided with openings 15 for receiving the pipes 8. A radiating fin 16 of the required area has its upper end bent and provided with openings 17 for receiving the stub pipes 8'. Figure 3 shows how the pipes 7 and 7' and 8 and 8' are fastened for partially telescoping within each other for forming a joint. The joining of the plates 9 and 11 and the plates 10 and 16 form housings which receive the joints of the pipes. These housings are provided with openings 18 (see Figure 4) for permitting lead in a molten state to be poured around the pipe joints, thereby providing a gas-tight seal when the lead cools. Figure 4 also shows partitions 19 as

being disposed along the sides of the pipes for permitting the lead to be confined to the space directly adjacent to the pipe joints. This sealing of the joints is preferably done prior to the installation of the device in the storage compartment. The bend or rib 12 prevents sagging of the fin 11 and also prevents warping of fins 9 and 11. Fewer screws 24 will therefore be required in securing the fins to the box.

The sloping of the plate 11 toward the plate 10 is for causing any condensations to flow onto the plate 10 and from there to the plate 16 where it drops into a water outlet 20. Moreover, the inclination of the plate 11 causes the air to move from the right to the left when looking at Figure 1 and, therefore, keeps this air hugging the plate 11 and carries it to the plates 10 and 16.

A baffle plate 21 connects the plates 11 and 10 together. Openings 22 permit condensations forming upon the top of the plate 11 to flow onto the top of the baffle plate 21 and there be conveyed to the plate 10 and the plate 16 by means of openings 23 (see Figure 4).

The openings 23 also permits the pipes 8' to extend thru the baffle plate 21.

From the foregoing description of the various parts of the device, the operation thereof may be readily understood. The refrigerant will flow from the tank 3 thru the pipes 7' and 7 and will expand in the tubes, returning as gas to the header, and also the pipes 8' and 8 and back to the header, thereby cooling the pipes. The pipes, in turn, cool the radiating fins by conduction. The flow of air in the box is shown by the arrows in Figure 1. The disposing of the plates across the top and one side of the box creates a forced circulation, and this circulation is so rapid that there is not so great a difference in temperatures at the lower right hand corner of the box and at the upper left hand corner of the box as there is in standard devices. The pipes 7 and 8 can, therefore, be kept at a temperature well above the frosting point. An insulating layer of frost will, therefore, not form upon the pipes. This obviates the necessity of melting away the frost from time to time and also permits the refrigerant to have a direct cooling effect upon the air within the box.

I have already mentioned how the device takes up less space than the standard machine, which takes up anywhere from one-fourth to one-third the space which should be used for storage purposes. The pipes 7 and 8 can be made larger for the freer flow of the refrigerant therethru because the air does not have to pass between the pipes as is the case with the standard machine. This does away with the necessity of forcing all the air thru small openings. It should be borne in mind,

due to the fact that the pipes extend across

the top and one side of the box, that the area of the pipes may be increased without decreasing the food storage space. Screws 24 are used for securing the device to the walls. The tank 3 is supported by straps, not shown. A brine tank may be disposed between the pipe 7' and the top of the box, and a drawer may be disposed in this brine tank for holding water for preparing artificial ice. The drawer 25 is shown in Figures 1 and 3.

It should be noted that the plate 16 has openings 26 therein for permitting the air to pass therethru and be more quickly cooled by contacting with both sides of the plate or fin.

I claim:

1. The combination with a storage compartment, of an expansion header disposed in the upper corner of said compartment, and expansion pipes extending from said header across the top of the compartment and in close proximity to the ceiling, and radiating fins secured to said pipes and extending substantially in the plane of the compartment ceiling.

2. The combination with a storage compartment, an expansion header, and expansion pipes communicating with said header, some of said pipes extending in close proximity to the ceiling and other of the pipes extending in close proximity to a side wall of said compartment, and radiating fins secured to said pipes and extending substantially parallel with the ceiling and one wall of the compartment.

3. The combination with a storage compartment, an expansion header, and expansion pipes communicating with said header, some of said pipes extending in close proximity to the ceiling and other of the pipes extending in close proximity to a side wall of said compartment, and radiating fins secured to said pipes and extending substantially parallel with the ceiling and one wall of the compartment, said fins being of the required area for cooling the compartment without taking up any additional storage space.

4. A device of the type described, comprising an expansion header, two sets of expansion pipes extending substantially at right angles to each other, and radiating fins of different sizes securable to said pipes for causing the fins to extend substantially at right angles to each other.

5. The combination of a storage compartment, with an expansion header disposed in the upper corner of said compartment, cooling coils extending from said header, some of said coils being disposed in close proximity to the top and other of the coils extending in close proximity to a side wall of said compartment, and radiating fins secured to said pipes, the upper fin being inclined downwardly at an angle toward said side fin.

6. The combination of a storage compartment, with an expansion header disposed in the upper corner of said compartment, expansion coils extending from said header, some of said coils being disposed in close proximity to the top and other of said coils extending in close proximity to a side of said compartment, and radiating fins secured to said pipes, the upper fin being inclined downwardly at an angle toward said side fin, a water outlet for said compartment, and means for admitting any condensation on said fins to flow into said outlet.

In testimony whereof I affix my signature.
